(57) **CLAIM**

The ornamental design for a display screen with animated graphical user interface, as shown and described.

DESCRIPTION

FIG. 1 is a front view of a first image in a sequence for a display screen with animated graphical user interface; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; FIG. 8 is a front view of an eighth image thereof; FIG. 9 is a front view of a ninth image thereof; FIG. 10 is a front view of a tenth image thereof; and, FIG. 11 is a front view of an eleventh image thereof. The appearance of the animated graphical user interface sequentially transitions between the images shown in FIGS. 1-11. The process or period in which an image transitions to another forms no part of the claimed design. The broken lines illustrate an electronic device with display screen, as well as portions of a graphical user interface, and form no part of the claimed design.
